UNITED STATES PATENT OFFICE.

JOHN S. TIMMONS, OF PHILADELPHIA, PENNSYLVANIA.

TELEPHONE RECEIVER.

Application filed February 25, 1922. Serial No. 539,069.

To all whom it may concern:

Be it known that I, JOHN S. TIMMONS, a citizen of the United States, residing in Philadelphia, Pennsylvania, have invented 5 a Telephone Receiver, of which the following is a specification.

One object of this invention is to provide a novel form of sound amplifier for use in connection with a telephone receiver, which 10 shall be not only highly efficient under operating conditions, but shall also be simple, inexpensive and compact in construction.

It is further desired to provide a form of sound amplifier which in addition to the 15 above characteristics, shall include a horn of novel construction, together with novel means for supporting and concealing the same, as well as protecting it and its associated telephone receiver.

20 These objects and other advantageous ends I attain as hereinafter set forth, reference being had to the accompanying drawings, in which,

Fig. 1 is a perspective view illustrating 25 the containing casing forming part of my invention;

Fig. 2 is a side elevation partly in vertical section, illustrating the detail construction of my device; and

30 Fig. 3 is a plan of the horn with its attached screen.

In the above drawings, 1 represents a box or casing preferably of wood, which may be highly polished or suitably ornamented as 35 desired and which has one end 2 removably held to it by a series of screws 3. This end has formed in it a substantially rectangular or other suitably shaped opening covered by a relatively fine mesh wire screen 4.

40 This front end 2 of the box also has attached to it and supports a coiled sound amplifying device in the form of a metallic or other suitable horn 5, preferably though not necessarily of rectangular cross section and so 45 formed that its small end is curved or formed in such shape as to extend through its body portion.

The large end of said horn is rigidly connected to the end 2 of the box and has substantially an area of opening equal and 50 similar in form to that in the box end, with which it is connected by bolts 6 and from which it is acoustically insulated by cushioning material such as cork or the like. Fixed in any suitable manner to the small end of 55 the horn, which in this case protrudes from the lower side of the body, is a loud speaking or other suitable telephone receiver 7 which may be of any desired construction. The terminals for this receiver are connected 60 to two binding posts 8 and 9 mounted in the present instance on the lower portion of the end 2 of the container 1.

From the above description it will be seen that a given length of horn 5 is disposed 65 in a relatively compact manner such that while occupying the minimum of space, it none the less gives a relatively great amplification of the sounds produced by the receiver 7. The latter occupies an otherwise 70 vacant space in the casing, which is preferably of rectangular section and altogether the whole instrument is substantial, efficient and compact.

I claim:

1. A sound amplifying device comprising a horn of graduated diameter coiled intermediate its ends in the direction of its length, the small end of the horn intersecting and extending through the larger 80 portion of the horn and lying in the plane defined by the convolution of the coil.

2. A sound amplifying device comprising a horn having a reduced sound receiving end and an enlarged sound discharging end, 85 said horn being coiled intermediate its ends in the direction of its length, the smaller end of the horn intersecting and extending diametrically through the larger portion thereof, whereby the convolution of the coil 90 is confined to a single plane transverse to the plane of the discharge orifice of the horn.

JOHN S. TIMMONS.
